R. S. THOMPSON

MASSAGING DEVICE

Filed June 18, 1925

UNITED STATES PATENT OFFICE.

RALPH S. THOMPSON, OF NEW YORK, N. Y.

MASSAGING DEVICE.

Application filed June 18, 1925. Serial No. 38,005.

To all whom it may concern:

Be it known that I, RALPH S. THOMPSON, a citizen of the United States, residing in the city, county, and State of New York, 55
have invented certain new and useful Improvements in Massaging Devices, of which the following is a specification.

This invention relates to a massaging device of the vibrating type, and has for its 60
10 object to provide, a device as hereinafter set forth, for intensifying the action of the rolling massage principle in the reduction of adiposity.

A further object of the invention is to 65
15 provide, in a manner as hereinafter set forth, a device of the class referred to, including a body traversing element having an uneven working face and revolved on the manual application of pressure thereto, and 70
20 with the device further including a vibration creating element actuated from and during the travel of the traversing element to provide an intermittent resistance to the travel of the traversing element, thereby 75
25 setting up a braking action to amplify the massage function of the device.

A further object of the invention is to provide, in a manner as hereinafter set forth, a device of the class referred to, for traversing the human body and operated on the manual application of pressure thereto, and whereby the massage function of the device is amplified by providing a braking action at right angles to the direction in 80
30 which the device is traversing the human body.

Into the surface of the device is molded a succession of re-entering waves of sufficient prominence to reach deeply through the 85
40 layers of the skin and exert a compressing effect on adipose tissue deposited at substantial depth from the body surface. By virtue of the inherent resistance to the rotation of the device, this simple compression 90
45 is converted into a kneading massage action. The effectiveness of this action good in itself, is enhanced many fold by the vibrating property of the device which firmly percusses the area many times per second.

50 These complex mechanical actions result in physically dislodging fat molecules from their storage place as adipose tissue, in stimulating an active blood circulation

through the treated area, and in setting in operation natural processes for the substitution of firm muscular tissue in place of the previously existing adiposity.

Further objects of the invention are to provide, in a manner as hereinafter set forth, a massaging device, which is simple in its 95
construction and arrangement, strong, durable, compact, thorough efficient in its use, conveniently operated, readily assembled, and inexpensive to manufacture.

With the foregoing and other objects in view, the invention consists of the novel construction, combination and arrangement of parts, as hereinafter more specifically described and illustrated in the accompanying drawings, wherein is shown an embodiment of the invention, but it is to be understood that changes, variations and modifications can be resorted to which come within the scope of the claims hereunto appended.

In the drawings wherein like reference characters denote corresponding parts throughout the several views:

Figure 1 is a longitudinal sectional view of a massaging device, in accordance with 80
this invention.

Figure 2 is a fragmentary view, in longitudinal section, of the device upon an enlarged scale.

Figure 3 is a section on line 3—3, Figure 2.

Referring to the drawings in detail, 1 denotes a cylindrical tube of substantial length and diameter and constructed of any suitable material, preferably sheet metal of the desired gage. One end of the tube 1 is closed by a flanged cap 2, which is fixedly secured in position, by any suitable means, and is formed centrally with a circular opening 3. Mounted in the other end of the tube 1 is a cup-shaped member referred to generally by the reference character 4, which constitutes a driving element and consists of a cylindrical body portion 5, having a closed outer end 6, and with its inner end open. The body portion 5 snugly engages throughout the inner face of the tube 1, and said member 4 is fixedly secured to the tube 1 by hold-fast devices 7, in the form of screws having their heads countersunk in the body of the tube 1. The closed end 6 of the member 4 is flush with the edge of the tube 1, and said end 6, centrally thereof, is pro-

vided with a circular opening 8. The edge, at the inner end of the body portion 5, is toothed throughout, as indicated at 9, forming a circular gear rack for a purpose to be presently referred to.

The tube 1 is provided with an uneven resilient working face for traversing the human body when the device is performing its massaging function, and said uneven resilient working face is provided by a sleeve 10 of the same length as the length of the tube 1, as well as completely enclosing the latter and secured therewith in any suitable manner. The outer face of the sleeve 10 can be formed in any manner to provide its periphery other than plane, and by way of example the outer face of the sleeve 10 is illustrated as formed of lengthwise extending rows of corrugations and with the high and low parts of one row alternately disposed with respect to the high and low parts of an adjacent row, as indicated at 11, 12, 13 and 14. See Figures 1 and 3. The sleeve 10 can be formed of india rubber, sponge rubber of a moderate degree of porosity, or of any other resilient material not easily damaged by salves, creams or other medical preparations applied to that portion of the body which is to be massaged.

The elements 1, 2, 4 and 10 provide what may be termed a body traversing means and is mounted to revolve and is revolved on the manual application of pressure thereto, in a manner as hereinafter referred to.

The traversing element is loosely mounted on a pair of lengthwise aligning spindle members, referred to generally by the reference characters 15, 16. The member 15 consists of a cylindrical portion 17 and a squared portion 18 which is integral with the inner end of the portion 17 and abuts against the inner face of the cap 2. The portion 17 extends through the opening 3 in the cap 2. The portion 18 is of a length to terminate at a point between the transverse center of the tube 1 and the inner end of the member 4. The spindle member 16 includes a cylindrical portion 19 and a squared portion 20, which abuts against the inner face of the closed end 6 of the member 4. The cylindrical portion 19 extends through the opening 8 formed in the closed end 6 of the member 4. The portion 20 of the spindle member 16 is of materially less length than the portion 18 of the spindle member 15. The inner ends of the portions 18 and 20 oppose and are spaced from each other and further are connected together by a pair of oppositely disposed combined coupling and supporting elements referred to generally by the reference characters 21, 22, and as each of said elements is of the same construction but one will be described, as the description of one will apply to the other. Each of said elements is formed

from a flat metallic bar of substantial length, standing on edge, and comprises a pair of oppositely extending end portions 23, 24, a pair of oppositely extending inclined intermediate portions 25, 26, and a central portion 27, having an inset part 28 which merges into the outer end of an intermediate portion 26. The outer end of the intermediate portion 25 merges into the non-inset part of the central portion 27 and also into the inner end of an end portion 23. The intermediate portion 26 terminates in the inner end of the other end portion 24. The end portions 23 of said elements are positioned against the sides, at the inner end, of the portion 18 of the spindle member 15 and secured thereto by the transversely extending hold-fast devices 29. The end portions 24 of said elements are positioned against the sides throughout of the portion 20 of the spindle member 16 and are secured thereto by the transversely extending hold-fast devices 30. The elements 22, 23 couple the spindle members together and also provide a supporting means for a transmission mechanism for operating a vibration creating means, and the latter and said mechanism will be presently referred to. The portions 17 and 19 of the spindle members project outwardly a substantial distance respectively from the cap 2 and closed end of the member 4, and each has secured thereon, as well as being enclosed thereby, through the medium of a holdfast device 31, a handle member 32 which abuts against the cap 2 or closed end 6 of the member 4. The spindle members are arranged at the longitudinal axis of the tube 1 and the said members in connection with the supporting elements 22, 23, are prevented from lengthwise shifting with respect to the tube 1, owing to the manner of setting up the portions 17 and 19 of the spindle members and the handle members 32 with respect to the cap 2 and closed end 6 of the member 4. The offset parts 28 of the elements 22, 23, for a portion of their length, extend into the member 4. The intermediate portions 26 and end portions 24 of the elements 22, 23, and the portion 20 of the spindle member 16 are arranged within the member 4.

The transmission mechanism for operating the vibration creating means is operated from the driving element formed by the member 4, and said transmission mechanism comprises a shaft 33 which is journaled in openings 34' formed in the inset parts 28 of the elements 21, 22. The shaft 33 is positioned clear of the inner end of the member 4, but in proximity to the bevelled teeth 9 arranged on the inner edge of the body portion 5 of the member 4. The shaft 33 projects outwardly from each inset part 28 and one of its projecting ends carries a bevelled pinion 34, which is in mesh with the teeth 9.

The pinion 34 is fixed to the shaft 33. Fixed to the shaft 33, between the inset parts 28, is a sleeve 35, provided centrally thereof, with a large gear wheel 36, which extends 5 into the inner end of the member 4 but is of a diameter to clear the inner face thereof. When a rolling or revolving action is manually applied to the traversing element, the member 4 is revolved bodily therewith, and 10 during the revolving of the member 4 the teeth 9 acting on the pinion 34 will revolve the shaft 33 which carries the gear wheel 36 therewith. The gear wheel 36 is revolved on an axis at right angles to the axis of the 15 traversing element.

The vibration creating means or mechanism comprises a revoluble shaft 37, which is journalled in the non-inset parts of the central portions 27 of the elements 22, 23. 20 Fixed to the shaft 37, centrally thereof, is a pinion 38, meshing with the gear 36, whereby on the operation of the latter the shaft 37 will be revolved. The shaft 37 has fixedly secured thereto a pair of spaced vibrating 25 members 39, 40, and each of said members is eccentrically mounted on the shaft 37 and is interposed between the pinion 33 and the non-inset part of the central portion of a combined coupling and supporting element. 30 Each of said members consists of a weight in the form substantially of a quarter of a sphere and with their inner sides slightly inclining in opposite directions as indicated at 40', 41. The inner side of the member 35 39 is oppositely inclined with respect to the inner side of the member 40 thereby providing a space between said members 39 and 40 gradually increasing in width from the center thereof towards each end to form a clearance 40 for the gear 36 when the members 39 and 40 are carried with the shaft 37. The weight members 39, 40 and shaft 37 extend at right angles to the longitudinal axis of the traversing element.

45 The eccentrically mounted members 39 and 40 provide a resistance to the revolving movement of the traversing element, the resistance acting as an intermittent braking action and which amplifies or intensifies the 50 massage function of the device. The braking action is at right angles to the direction of travel of the traversing element, or rather at right angles to the axis of the traversing element.

55 The transmission mechanism provides for the driving of the shaft 37 at a much higher speed than the revolving movement of the traversing element, and as the members 39 and 40 are mounted eccentrically they tend to impart violent movements or shocks to the structure, or in other words create vibration, and with the shock imparted in a direction at right angles to the direction of travel of the traversing element and which intensifies the massage function. The re-

silient uneven working face of the traversing element further assists in intensifying the action of the rolling massage principle.

The purpose, use and advantages of the device, in accordance with this invention, have been hereinbefore referred to, and although the preferred embodiment of the invention is as illustrated and described, yet it is to be understood that changes in the details of construction can be had which will fall within the scope of the invention as claimed.

What I claim is:—

1. A massaging device for the purpose set forth comprising a revoluble traversing element provided with an uneven resilient working surface, and a vibration creating means arranged within operatively connected with and driven from said element on the revolving of the latter in a direction at right angles to the travel of said element. 80

2. A massaging device for the purpose set forth comprising a revoluble tubular traversing element provided with a working surface for contact with the human body during the traversing of said element, and means arranged within said element between the transverse center and one end thereof for imparting a vibratory action during the traversing of said element, said means operatively connected with and driven from said element on the revolving of the latter. 85 95

3. A massaging device for the purpose set forth comprising a revoluble tubular traversing element provided with a resilient working surface, and revoluble means arranged within said element for creating a vibratory action on the revolving of said element, said means operatively connected with and driven from said element and revolving in a direction at right angles to the axis of said element. 100 105

4. A massaging device for the purpose set forth comprising a revoluble traversing element and means arranged within operatively connected with said element, said means driven from said element on the revolving thereof for creating a vibratory action, said means operating in a direction at right angles to the axis of the traversing element. 110 115

5. A massaging device comprising a body traversing element in the form of a tubular structure of substantial length, manually engageable means projecting from each end of said structure for it, and means connected to said manually engageable means operatively connected with and arranged within said structure and driven therefrom on the revolving of the structure to provide successive vibrations during the travel of said element in a direction at right angles to the travel of said element. 120 125

6. A massaging device comprising a body traversing element in the form of a tubular structure of substantial length, manually en-

gageable means projecting from each end of said structure for revolving it and means connected to said manually engageable means operatively connected with and arranged 5 within said structure and driven therefrom on the revolving of the structure to provide successive vibration during the travel of said element, the said means for providing successive vibrations including a driven shaft 10 extending at right angles to the axis of said structure.

7. A massaging device comprising a body traversing element in the form of a tubular structure of substantial length, manually engageable means projecting from each end of said structure for revolving it, means connected to said manually engageable means operatively connected with and arranged within said structure and driven therefrom 15 on the revolving of the structure to provide successive vibrations during the travel of said element, and said structure provided with an uneven resilient working face contacting with the surface over which said structure traverses.

8. A massaging device for the purpose set forth comprising a revoluble traversing element formed of a tubular structure, means extending from each end of said structure 30 for manually revolving it, said structure loosely mounted on said means, a shaft arranged within said structure and supported by said means, a pair of weight members carried by said shaft and eccentrically connected thereto, and means arranged within said structure, operatively connected therewith and driven therefrom and operatively engaging with said shaft for revolving it during the travel of said structure thereby 35 providing for said weight members to create successive vibrations during the travel of the structure.

9. A massaging device for the purpose set forth comprising a manually revoluble hollow roller, a driving element secured therein 45 at one end thereof, a pair of spaced spindle members, one having one end of said roller

revolving thereon and the other having said element revolving thereon, a pair of oppositely disposed combined coupling and supporting elements secured to the inner ends of said members, a vibrating mechanism revolvably mounted in said supporting elements, and a transmission mechanism revolvably mounted in said supporting elements, operatively connected with and driven from said driving element and having a driving connection with said vibrating mechanism.

10. A massaging device for the purpose set forth comprising a manually revoluble hollow roller, a driving element secured therein at one end thereof, a pair of spacing spindle members, one having one end of said roller revolving thereon and the other having said element revolving thereon, a pair of oppositely disposed combined coupling and supporting elements secured to the inner ends of said members, a vibrating mechanism revolvably mounted in said supporting elements, a transmission mechanism revolvably mounted in said supporting elements, operatively connected with and driven from said driving element and having a driving connection with said vibrating mechanism, and said vibrating mechanism including a pair 65 of spaced, eccentrically mounted weight members each substantially in the form of a quarter of a sphere.

11. A massaging device for the purpose set forth comprising a manually propelled hollow cylindrical roller, a revoluble shaft arranged diametrically thereof, a pair of spaced weight members eccentrically fixed to said shaft and each substantially in the form of a quarter of a sphere, means arranged within operatively connected with and driven from the roller for revolving said shaft during the propelling of the roller, and supporting means common to said roller, shaft and driving means.

In testimony whereof, I affix my signature hereto.

RALPH S. THOMPSON.
